CLAIM

The ornamental design for a nasal dilator with relief cuts, as shown and described.

DESCRIPTION

FIG. 1 is a top plan view of a first embodiment of a nasal dilator with relief cuts showing my new design in the unflexed state;

FIG. 2 is a three-quarter perspective view thereof;

FIG. 3 is a top plan view showing my new design in the slightly flexed state;

FIG. 4 is a right side view shown in an in-use state;

FIG. 5 is a top plan view of a second embodiment of a nasal dilator with relief cuts showing my new design in the unflexed state;

FIG. 6 is a three-quarter perspective view thereof;

FIG. 7 is a top plan view showing my new design in the slightly flexed state; and,

FIG. 8 is a right side view shown in an in-use state.

The broken line showing of human facial features is directed to environment and is for illustrative purposes only; the broken lines form no part of the claimed design.

The bottom view of the article is not shown in the drawings nor described in the specification. It is understood that the appearance of any part of the article not shown in the drawing or described in the specification forms no part of the claimed design.
